INVENTOR,
Peter De Vries;
BY Raymond H. Myrick,
ATTORNEY.

Patented Sept. 9, 1924.

Des. 65,562

UNITED STATES PATENT OFFICE.

PETER DE VRIES, OF LOS ANGELES, CALIFORNIA, ASSIGNOR TO C. B. VAN VORST COMPANY, OF LOS ANGELES, CALIFORNIA, A CORPORATION OF CALIFORNIA.

DESIGN FOR A BUREAU.

Application filed August 10, 1921. Serial No. 491,282. Term of patent 3½ years.

To all whom it may concern:

Be it known that I, PETER DE VRIES, a citizen of the United States, residing at Los Angeles, in the county of Los Angeles and State of California, have invented a new, original, and ornamental Design for Bureaus, of which the following is a specification, reference being had to the accompanying drawing, forming part hereof.

The drawing is a perspective view showing my new design for bureaus.

I claim:

The ornamental design for a bureau, as shown.

PETER DE VRIES.

Witnesses:

N. E. FULKERSON,
MARIAN ASKIN.
